FIRE HOSE CLAMP

William L. Bjarnson, North Bend, Oreg.

Application June 3, 1940, Serial No. 338,571

2 Claims. (Cl. 251—5)

My invention relates to a clamp, adapted for cutting off the flow of water thru broken fire hose or such hose under pressure, in which the hose is clamped together between a platen and a jaw constituting one arm of a lever of the first order whose cooperating power arm is adapted to keep the jaw open when the power arm is free from pressure which is applied thereto by a second lever of the first order and held thereupon by moving the weight or lift arm of said second lever to an off-center position.

An object of my invention is to provide a lighter, cheaper, and more simplified structure in this art.

A further object is to provide such a structure which is open when not under pressure and which is locked shut when under pressure.

A still further object is to provide the last named structure wherein such features are inherent features of the basic members and not due to additional auxiliary members.

Such a structure is illustrated in the accompanying drawing in which Fig. 1 is a plan view; Fig. 2 is a side view; Fig. 3 is a section on 3—3 of Fig. 2; and Fig. 4 is a side view of a roller equipped weight or lift arm.

Throughout the drawing and the specification similar numerals refer to similar parts.

The clamp comprises a base A which may be designed in a number of ways and constructed as a one-piece casting or built up of sections welded together. For purpose of illustration we shall consider it as being a casting. This base A has two side bars 1 and 2 of rectangular cross section secured together by the spreaders 3, 4, 5, and 6, and by the foot pads 7 and 8 positioned at each end on the bottom face 9 of said side bars. Bridging the gap between the spreaders 3 and 4 and the side bars 1 and 2, is a concave platen or fixed jaw 10 upon which a hose 11 is positioned when the same is being clamped to shut off the water flowing therethru.

This is brought about thru the agency of the first order lever B fulcrumed on a pin 12 riveted in the ears 13 on the side bars 1 and 2. The pin 12 has a bearing in the lever B formed by a bushing 14 press-fitted in said lever and extending therefrom to form the bosses or portions 15 whereby the clearance 16 is held between the lever B and the side bars 1 and 2.

The front end of the lever B is a T-shaped section 17 comprising a convex jaw 18 whose bottom 19 is formed substantially parallel to the concave top face 20 of the platen 10 when the average hose to be worked upon is completely

closed together as shown in Fig. 2. The rib 21 completes the T-shaped section 17 and acts as a stiffener for the jaw portion 18 and at the same time permits the jaw portion 18 to be cut down in weight without sacrificing too much strength. The jaw 18 is made lighter than the power arm portion 22 or the weight of said power arm is so distributed as to overbalance the jaw. The power arm 22 is raised by the weight or lift arm 23 of a second lever of the first order in the form of a bell crank.

This bell crank C is fulcrumed on the pin 24 riveted in the side bars 1 and 2. This pin 24 has a bearing in the bell crank formed by a bushing 25 press-fitted in said bell crank and extending therefrom to form the bosses or portions 26 whereby the clearance 27 is held between the bell crank C and the side bars 1 and 2. The power arm 28 of said bell crank is formed with a socket 29 into which the end of the bar 30 may be inserted when it is desired to operate the clamp. This lever is made of a length which, together with the weight or power applied to its end 31, is sufficient to cause the jaw 18 to act upon the hose 11 to close it against the flow of water thru it. The spreaders 4, 5, and 6, may be pierced so that the bar 30 may be positioned as shown by its dot and dash outline D when the clamp is not in use. The end of the lift arm 23 is rounded or semi-circular in form whereby its transition from one position to another on the bottom cam face 32 of the power arm 22 is smooth. The face 32 is shown straight for a major portion of its length forward of a slight bulge 33 which merges into a short curved length 34 scribed by the rounded end 35 of the arm 23 as it is moved beyond the center 36 into a position as shown in Fig. 2. When in this off-center position, the rounded end 35 lies behind the bulged portion 33. This position is reached prior to the engagement of the power arm 28 with the spreader 6 which acts as a stop and limits the movement of said power arm. The movement of this arm in the opposite direction is limited due to its co-operating arm 23 coming into contact with the spreader 5. The arm 23 is also made of greater weight than the arm 28, or its weight so distributed that it will over-balance said arm 28, whereby the arm 23 will automatically come to rest against the spreader 5 whenever its rounded end 35 is not behind the bulge 33, or in other words, when the arm 23 is off-center. As the arm 23 lowers, the arm 22 follows it down automatically whereby the jaw portion 18 will be in a raised position spaced from the platen 10 ready for the reception of a

hose 11 to be acted upon. The arm 22 because of its position and structure serves as a hand grip in carrying or moving the clamp about.

The end of the arm 23 may be provided with a roll 37 whereby rolling friction is substituted for the sliding friction between the end 35 of the arm 23 and the bottom face 32 of the arm 22.

It is to be noted that the platen 10 is of greater width than the hose 11 when it is flattened out when closed. Both the platen and the jaw should be designed to take the largest hose to be worked upon. It is also to be remarked that the bulge 33 is not altogether necessary to lock the arm 23 provided its centerline 38 is brought sufficiently past the normal center 36. To pass the arm 23 beyond the bulge 33, the compressibility of the hose 11 is taken advantage of and hence the hose should be completely closed when the end 35 is behind the bulge 33 which in reality is a safety measure against un-premeditated movement of the bar 30 upwards. Any such movement is also acted against by the energy stored up in the compressed rubber of the hose if such material is used in the hose construction. It is also to be noted that the end 31 of the bar 30 is moved downward to apply pressure to the jaw 18 which also moves in the same direction. In other words, the pressure is down against the ground or support for the clamp.

The clamp illustrated is one-half size. I have repeatedly used this clamp to cut off 2½" hose carrying 125 pounds pressure which is the maximum our small town pumper will deliver. I believe this same clamp will cut off much greater pressures. However, it is obvious that it is merely a matter of size and leverage when it comes to meet the conditions imposed. The operation of the clamp is obvious without further comment.

What is new over the art is embodied in the following claims.

I claim:

1. A fire hose clamp comprising a base, a fixed jaw on one end of said base, a lever of the first order pivotally secured to the base and comprising a jaw portion formed to cooperate with said fixed jaw and a power arm, a second lever of

the first order pivotally secured to the base adjacent the other end thereof and formed as a bell crank comprising a lift arm adapted to engage the lower face of the power arm of the first lever and a power arm to which to apply downward pressure whereby a similar movement of the jaw portion is effected to compress a hose placed transversely therebetween, the power arm of the first lever and the lift arm of the second lever each being heavier than the other arm of the respective levers to over-balance the opposite ends of said levers whereby to cause the jaw portion to be raised from the fixed jaw ready for the reception of a hose therebetween until downward pressure is applied to the power arm of the second lever, the free end of said lift arm being movable to an off-center position to releasably lock the levers in their hose-compressing positions.

2. A fire hose clamp comprising a base, a fixed jaw on one end of said base, a lever of the first order pivotally secured to the base and comprising a jaw portion formed to cooperate with said fixed jaw and a power arm provided with a projection on its lower face, a second lever of the first order pivotally secured to the base adjacent the other end thereof and formed as a bell crank comprising a lift arm adapted to engage the lower face of the power arm of the first lever and a power arm to which to apply downward pressure whereby a similar movement of the jaw portion toward the fixed jaw is effected to compress a hose placed transversely therebetween, the power arm of the first lever and the lift arm of the second lever each being heavier than the other arm of the respective levers to over-balance the opposite ends of said levers whereby to cause the jaw portion to be raised from the fixed jaw ready for the reception of a hose therebetween until downward pressure is applied to the power arm of the second lever, the free end of said lift arm being movable to a position between the projection and the free end of the power arm of said first lever to releasably lock the levers in their hose-compression positions.

WILLIAM L. BJARNSON.
